SELF-LOCKING WINDOW LOCK

Leslie E. Tassell, Grand Rapids, Mich.

Application September 25, 1950, Serial No. 186,628

3 Claims. (Cl. 292—242)

1

This invention relates to an automatic, self-locking window lock which is used with windows having sliding sashes, and in which, when the sashes are moved to closed position, the lock will automatically move into operative locking position and not require manual turning of the locking member to engage with a keeper therefor, but will self engage therewith, providing assurance that when the window is closed the sashes will be locked together.

It is an object and purpose of the present invention to provide such automatic or self-locking window lock in a very practical and simple structure, which is sure and simple in its operation and which may be installed on the sashes of vertically sliding windows at the same places and in the same manner as non-automatic locks which, after a window is closed, have to be manually moved to locking position to insure that the sashes are securely locked and held against movement.

An understanding of the invention may be had from the following description, taken in connection with the accompanying drawing, in which,

Fig. 1 is a plan view of the lock and keeper of my invention shown together in locked position.

Fig. 2 is a horizontal section through the base of the lock, substantially on the plane of line 2—2 of Fig. 3, looking downwardly.

Fig. 3 is a side elevation of the lock shown in Fig. 1, the sash rails to which the lock and keeper are secured being in vertical section.

Fig. 4 is a rear elevation vertical section at right angles to the section shown in Fig. 3, taken substantially on the plane of line 4—4 of Fig. 3, looking in the direction indicated, and

Fig. 5 is a rear elevation of the lock and keeper the same as in Fig. 4, but with the lock and keeper separated, the two being shown in locked position in Fig. 4.

Like reference characters refer to like parts in the different figures of the drawing.

On the lower rail 1 of the upper sash of a vertically sliding window, the lock keeper is permanently secured. It includes a sheet metal base 2 from the upper side of which a keeper hook extends, having a generally vertical portion 3 at the upper end of which a ledge 4 is bent substantially at right angles and which terminates in a downwardly extending lip 5. The ledge 4 is inclined at a slightly acute angle to the horizontal plane of the upper side of the sash rail 1 on which the keeper is mounted.

2

On the upper side of the upper rail 6 of the lower sash the lock is mounted. It includes a sheet metal base 7 having a top and downwardly extending sides and ends. Over the top of the base 7, the movable locking member to engage with the keeper which has been described is pivotally mounted to turn about a vertical axis. It is made from sheet metal having a flat generally circular base 8, from which a curved vertical side or wall 9 extends upwardly around approximately one-half of the circumference of the base 8. At one end and away from the keeper such side 9 is extended outwardly in a handle 10 for manual engagement. At the other end the side or wall 9 is formed into a terminal lip 11 which has a cam edge 12, as shown in Fig. 5, located so that when for example, the lower sash has been lifted and is being moved down to closed position such edge will ride against a cooperating edge of the ledge 4 (Fig. 5) to thereby swing the locking member in a counter-clockwise direction from its pivotal mount on the base 7 (which will hereafter be described), moving lip 11 back of such edge of the ledge 4 so that it may be received and moved underneath to engage with the keeper and lock the two sashes against vertical separating movement of either of such sashes. The base 8 is cut away opposite handle 10, as shown in Fig. 1, for a distance making a recess, so that the base when properly located with reference to the lip 11 may move upwardly relative to the keeper, the projecting lip 5 and part of the ledge 4 passing through such recess. The ledge 4 is at one end portion of the recess or part cut from the base 8. At the other end portion of the said recess a short wall 13 of arc shape form, similar to but shorter than the wall 9, extends upwardly having its upper edge of a curved cam form as shown at 14, the edge 14 and the cam edge 12 of the two wall sections 9 and 13 being substantially parallel.

The base 8 has a centrally located headed pivot 15 extending therethrough which is of out-of-round form where it passes through the base. Such pivot pin extends downwardly into the base 7 and carries, at its lower end, a head 16 which has two opposed flat sides. A leaf spring having a middle section 17 bears one against each of the flat sides 16 (Fig. 2), while the end portions 18 of such leaf springs are of curved form to correspond to the rounded end portions of the housing 7.

The leaf springs when free to operate hold the head 16 in central position, as in Fig. 2, with the movable lock member in its central, normally

3

locking position as in Fig. 1, and as shown in dashed lines in Fig. 2. When the lock is manually operated by swinging the handle 10 to the left to release it from the keeper, both of the springs 17 are stressed so that upon release of the handle 10 the locking member returns to its initial position. On manually turning the locking member or lever to release from the keeper the sashes may be moved either by lifting the lower sash, this being most commonly done, or lowering the upper sash, or both sashes may be vertically moved, the lower sash upwardly and the upper sash downwardly.

If the upper sash has been lowered, or if the lower sash has been raised, on moving them to bring the sash rails 1 and 6 together, as in Fig. 3, the lock is turned counterclockwise from the position shown in Fig. 1 by the engagement of an end edge of the ledge 4 against the cam edge 12 of the wall 9, thereby turning the head 16 and stressing the springs 17 until the point or nose of the lip 11 passes to a position underneath the ledge 4. The springs thereupon automatically swing the lever in the opposite or clockwise direction and the lip 11 passes underneath the ledge 4 so that the two sash members 1 and 6 are automatically locked against separation. It will be noted that the upper edge of the wall 9 rides against the lower side of the ledge 4.

After the lock has automatically operated as described, the projecting handle 10 may be manually engaged to turn the movable locking member still further in a clockwise direction. But irrespective of whether the lock is as tightly locked as may be desired through the self-locking or automatic action described, and whether or not subsequently the locking member is manually operated to make a tighter connection of the movable member with the keeper, the lock is automatic in its operation and the keeper engagement is amply sufficient to insure that the sashes are locked together and cannot separate by a vertical movement of one relative to another until the locking member is moved to released position.

If on turning the pivotally mounted locking member counter-clockwise from the position shown in Fig. 1 to the dash line position of the handle 10 at the right sufficiently that the intermediate stressed portions of the spring 17 bear upon the rounded end portions of the head 16, so that the head will not return under the pressure of the springs to its initial position shown in Fig. 2, such extreme of movement will bring the cam edge 14 of the wall section 13 underneath the opposite edge portion of the ledge 4. Thereupon on separating the sashes, upon relative vertical movement of one with respect to the other, the curved or cam edge 14 will ride against such opposite edge 4 and turn the locking member so that springs 17 will operate to complete the turning of the pivotally mounted locking member to central position as shown, in which position the lip 11 and its cam edge 12 will be located so as to engage with the first mentioned edge of the ledge 4.

The window sash lock shown and described is of a very practical, novel and useful structure. It is economically produced and insures the complete locking of vertical sliding window sashes so that the two adjacent rails, the lower rail of the upper sash, and the upper rail of the lower sash shall

be locked together, irrespective of whether or not the one closing the window thereafter manually moves the movable lock member to a tighter locking position.

5 The invention is defined in the appended claims and is to be considered comprehensive of all forms of structure coming within their scope.

I claim:

1. In a structure as described having, a keeper 10 adapted to be permanently secured at the upper side of a horizontal rail of a vertically sliding window sash, a locking member mounted to turn about a vertical axis adapted to be permanently secured to a horizontal rail of a second window sash, said two sashes being vertically slidable past each other, and said keeper having a hook portion extending a distance above the sash on which it is adapted to be secured, said locking member including a base of generally circular form and an upwardly extending member integral with the base at an edge thereof, the improvement comprising said member having at one end a terminating lip having an under cam edge above the base, said lip being adapted to pass underneath the hook portion of the keeper for locking the sashes together, yielding means associated with said locking member for normally holding it in the position it occupies when operatively connected with the keeper, said means yielding when, upon relative vertical movements of the sashes, the rails on which the keeper and locking member are adapted to be secured are brought into close proximity and the keeper and locking member have moving contact engagement, said cam edge riding against one side of the hook until it passes thereby, and thereafter being turned by the force of said yielding means into locking engagement with the keeper hook.

2. In a window latch including, a keeper, a movable locking member adapted to turn about a vertical axis, a base on which said locking member is mounted for turning movement, said locking member comprising a generally circular plate immediately over said base and an upwardly extending vertical wall partly around said plate, one end of said wall terminating in a lip, the improvement comprising said lip at its underside being curved upwardly and outwardly from the lower edge of the wall to the free end of said lip, and yielding spring means operatively connected with said locking member for normally holding it in a predetermined position, which is substantially the position which the locking member is to have when in locking engagement with the keeper.

3. A structure as defined in claim 2, and a second vertical wall or short length extending upward from said plate spaced a distance from said lip, said second upwardly extending wall having an upper edge of curved form extending downwardly from the upper end thereof toward said lip, said curved edge of said second upwardly extending wall and the lower curved edge of said lip being in generally parallel relation to and spaced from each other.
